UNITED STATES PATENT OFFICE.

FRIDERICH C. EBERLEY AND RUDOLPH RICHTER, OF DENVER, COLORADO.

CALORIFERE.

SPECIFICATION forming part of Letters Patent No. 267,781, dated November 21, 1882.

Application filed March 22, 1882. (No model.)

To all whom it may concern:

Be it known that we, FRIDERICH C. EBERLEY and RUDOLPH RICHTER, of Denver, in the county of Arapahoe and State of Colorado, have invented certain new and useful Improvements relating to Caloriferes, of which the following is a specification.

The accompanying drawings illustrate our improved calorifere, and represent what we consider the best means of carrying out our invention.

Figure 1 is an end elevation. Fig. 2 is a horizontal section taken across the furnace. Fig. 3 is a vertical longitudinal section. Figs. 4 and 5 are sections showing the boxes and pipes.

Similar letters of reference indicate like parts in all the figures.

In our invention we provide an arrangement of sheet-iron or clay pipes and boxes for the purpose of conveying smoke and heat through them until the latter have distributed and communicated the heat over the whole surface and then enter the smoke-flue through which the same is carried into the open air. This calorifere enables the operator to burn common soft coal or coke, as such may be had conveniently, and as it is frequently necessary to construct the apparatus in such a manner as to give a certain number of square feet of heating-surface, thus rendering it possible to calculate closely what amount and size of pipes may be used, (represented horizontally in the drawings;) but the pipes may in some circumstances, for the purpose of economy or convenience, be placed vertically, so that the course of heat and smoke in horizontal direction may be changed up and down ward for the conveyance of heat as may be required.

Having determined upon the number of feet of required heating-surface, we build the surrounding or inclosing walls *b b b* of common bricks, and convey fresh cold air through underground channels *a a* from the outside of the building into the space inclosed by the walls *b b b*, whence it is carried upward, having passed in contact with boxes *g g' g''* and pipes *fff* and been warmed thereby, and bring it into the room intended for its reception. These pipes *f* are all arranged in such a manner that, as nearly as possible, the upper pipe is placed right over the opening formed by two lower

ones, and the air is caused to move in a zigzag path, thus bringing it in contact with the entire heating-surface in its course upward.

To facilitate the thorough heating of the room, we provide four flues, *c c c c*, on the corners of the inclosing walls *b b b*, having openings *ddd* at their lower ends into the space formed by the walls *b b b*, thus allowing the cold air, which is naturally heavier than the hot air, to descend and come in contact with the said calorifere, to be either consumed by the fire or after being warmed to ascend again as hot air, thus completing the circulation. We provide besides the underground channels *a a* and flues *c c c* openings *r r r* of convenient size in the walls *b b b* to allow cold air to enter the enclosure of the furnace.

The conveying-pipes *ooo* are represented as of cast-iron and the boxes *g g' g''*, &c., and pipes *fff* as of sheet-iron; but all these can be made of earthenware in the manner as shown in conveying-pipes *ooo*, thus rendering a heat preferable for certain purposes—for instance, in malt-kilns, where a mild heat will produce an article of more value than a strong heat.

Our furnace is constructed in convenient form and size, with an ash-pit, *e*, inclosed by cast-iron outside walls, and a grate, *p*, over it. The sides of these walls are provided with ways *l*, in which move slides *k*, (shown by dotted lines in Fig. 3,) intended to cover the openings *m m m*, when desired. These slides are provided with rods passing through the brick walls *b b b* and furnished with grasping means *i*, allowing the operator to open or close the openings *m m m* at will for controlling the admission of air. The outside walls of the furnace *n*, above the grate, are lined with fire-bricks *h h*, for the better protection of the cast-iron of the structure whenever it is used and exposed to extreme heat. The whole is covered with a cast-iron hood or top, *p²*, as shown, and is perforated in the apex and furnished with a straight piece of pipe upward to receive the conveying-pipe *ooo*. This conveying-pipe *ooo* is to be made with elbows, as shown, and straight pieces, as may be dictated by necessity or convenience, the joints in the several sections of the same being packed with fire-clay and bolted together through

flanges. This pipe $o o o$ (or the elbows there-in) is further provided with openings and cov-
ers $p' p'$ on the lower side, as shown, to ad-
mit of being cleaned out, if necessary, and is
5 supported and kept in position by a cast-iron
column of suitable size. The front of the fur-
nace is formed by a cast-iron face-plate, hav-
ing hinge-hooks and catches cast on it solid,
for the reception of cast-iron doors, with re-
10 volving valves for the admittance of air either
above or below the grate. Upon this pipe $o o$
 o , or against the same at the flange Z , the box
 g is placed, and fastened and provided with
holes socketed, and pipes $s s s$, extending
15 through brick walls $b b$, for cleaning purposes,
and also socketed holes for horizontal convey-
ing-pipes fff , and a cover, tt , for the openings
 $s s$, to avoid counter drafts. From the box g the
conveying-pipes fff are carried into a simi-
20 lar box, g' , opposite the first one, g , the size
of these pipes fff being determined by the
area of the cross-section of the above-men-
tioned pipe $o o o$. From the box g' pipes lead
to the box g'' . The area of the cross section
25 of the upper set of pipes is equal to the area
of cross-section of the lower set of pipes, al-
though this second row of pipes contains one
more pipe than the first row, fff , and is divided
in such a manner that the pipes in the second
30 row will, as much as possible, be placed over
the openings between the pipes in the first
row. Thus these pipes are continued to such
a height as may be necessary to obtain the re-
quired amount of heating-surface. After plac-
35 ing the pipes in proper position the receiving-
box g is placed against the flange at Z or upon
the flange on top of conveying-pipe $o o o$. The
pipes fff are placed over the collars provided
for the purpose, the required height built up,
40 box g' placed on top, the larger-sized pipes f
 f built under it on the box g , &c., until the
whole is completed, when the last box, g'' , re-
ceives the smoke-pipe to convey the smoke

into the smoke-flue. For the support of the re-
ceiving-boxes $g' g''$, &c., wrought-iron brack- 45
ets xxx are provided, and built in the inclosing
walls $b b b$ in such a manner as to avoid any
possibility of their being pulled out of the
masonry by the weight upon them. These brack- 50
ets hold the boxes $g' g''$, &c., away from the in-
ner face of the masonry wall b , so as to allow
a liberal flow of the air to be warmed on all
sides of the boxes and make the whole sur- 55
face thereof available in heating the air. There
is liberty for the boxes to slide on the brack-
ets to allow for expansion and contraction.
The fact that the boxes are separate and dis-
tinct allows for an independent motion in ac- 60
commodating the expansion. It also makes
the top and bottom of each box an effective
heating-surface.

We claim as our invention—

1. In an air-heating furnace, the serpentine
pipes o between the fire-pot and a series of
straight flues, f , and boxes $g' g''$, &c., and hav- 65
ing cleaning-holes with caps p' at the lower
bends, combined and arranged as specified.
2. The separate boxes $g' g''$, held away from
inner face of the wall b by the brackets x , in
combination with the fire-pot and inclosing 70
masonry wall, and with the connecting-pipes
 $o f$, as herein specified.
3. The combination of the pipes f , box or flue-
head g , having cap-passages s and the flue o ,
provided with cleaning-openings having caps 75
 p' , substantially as set forth.

In testimony whereof we have hereunto set
our hands, at the city of Denver, Colorado, this
15th day of March, 1882, in the presence of
two subscribing witnesses.
